UNITED STATES PATENT OFFICE.

HARRY F. BERRY, OF LACONIA, NEW HAMPSHIRE; ASSIGNOR TO E. JENCKES MANUFACTURING COMPANY, OF PAWTUCKET, RHODE ISLAND, A CORPORATION OF RHODE ISLAND.

WEB-HOLDER FOR KNITTING-MACHINES.

No. 920,418.

Specification of Letters Patent.

Patented May 4, 1909.

Application filed July 17, 1908. Serial No. 443,954.

To all whom it may concern:

Be it known that I, HARRY F. BERRY, a citizen of the United States, residing at Laconia, in the county of Belknap and State of New Hampshire, have invented certain new and useful Improvements in Web-Holders for Knitting-Machines; and I do hereby declare the following to be a full, clear, and exact description of the invention, such as will enable others skilled in the art to which it appertains to make and use the same.

The invention relates to knitting machines, and more especially to the construction and arrangement of the web holders or sinkers which act to hold down the fabric as the needles rise through the loops during the knitting.

In circular knitting machines the web holders or sinkers are usually mounted and guided in radial slots formed in the upper end of the needle cylinder and in the sinker ring which is secured to the upper end of the needle cylinder. The sinkers are provided with web engaging fingers or hooks which overlie and hold down the loops of the fabric as the needles rise through them, and in order that the sinkers may effectively resist the upward strain to which they are subjected, it has been found desirable to provide devices for holding down the sinkers at their inner ends. In machines in which means are provided for retaining and holding down the sinkers at their inner ends as well as at their outer ends, the sinkers and retaining devices as heretofore constructed have presented opposing surfaces or shoulders so arranged that they move toward each other as the sinkers are advanced. These opposing surfaces form pockets or recesses in which the lint collects, so that it acts to resist the advance of the sinkers. The resistance offered by the lint produces wear and strain upon the sinkers and sinker operating cams, and the packing of the lint between the opposing surfaces will finally prevent the advance of the sinkers to the proper holding position, with resulting imperfections in the fabric being knit. It is necessary, therefore, for the operator to frequently remove the lint from between the opposing surfaces on the sinkers and their guiding and retaining devices, and this has also required the removal of the sinkers in the constructions heretofore in use. This

collection of lint, and the resulting wear upon the parts, and breakage of sinkers, and the necessity for frequent removal of the sinkers, has been a serious objection to the use of this type of sinker construction.

It is the object of the present invention to provide a construction of sinkers and guiding and retaining devices which is free from the objections outlined, and which is not subject to collection of lint in a manner which will interfere with the operation of the sinkers, or require their removal in order that any collection of the lint may be removed.

To this end one feature of the invention contemplates the provision of sinkers and retaining devices acting to hold down the inner ends of the sinkers so constructed and arranged that no opposing surfaces are presented upon the sinkers and the guiding devices which move relatively toward each other as the sinkers are advanced to holding position. No pockets or recesses are therefore formed in which the lint may collect and interfere with the advance of the sinkers. The specific construction and arrangement of the sinkers and cooperating retaining devices is not material to this feature of the invention in its broader aspects, and may be varied without departing from the invention. I prefer, however, to provide the sinkers with one or more fingers which extend rearwardly from their inner ends and pass radially outward through retaining slots formed in the upper end of the needle cylinder and cooperate with the slots in holding down the inner ends of the sinkers. This construction of sinker constitutes a further feature of the invention. With this construction of sinker, the slots or recesses in the sinkers between the fingers and body of the sinker, or between adjacent fingers, are open at their outer ends, so that there is no surface on the sinker opposing the outer periphery of the part of the cylinder in which the retaining slots are formed. The closed ends of the slots or recesses in the sinkers are within the needle cylinder where the lint is not liable to collect in them, and where any lint which may collect does not interfere with the advance movement of the sinkers, and may be readily removed without removing the sinkers. The sinkers are practically self cleaning, while both ends are efficiently

guided and retained against upward as well as lateral movement.

A further feature of the invention contemplates the provision in a construction in 5 which the sinkers are held down at their inner ends of a throat ring slotted on its upper and lower edges for the passage of the sinkers, and secured within the cylinder and forming its upper end.

10 The features of the invention will be readily understood from an inspection of the accompanying drawings, in which—

Figure 1 is a vertical sectional view through one side of a needle cylinder showing the preferred form of sinker construction, the sinker being shown in advanced or holding position; Fig. 2 is a similar view, showing the upper end of the cylinder with the sinker retracted in position for the drawing of the loops by 20 the needles; Fig. 3 is a side elevation of a sinker on an enlarged scale; Fig. 4 is a fragmentary view of the throat ring of the needle cylinder; and Fig. 5 is a vertical sectional view through the throat ring.

25 As shown in the drawings, the needle cylinder 1 is provided with the usual vertical grooves in which the needles 2 are mounted to reciprocate vertically. A sinker ring 3 is secured to the upper end of the needle cylinder, and is provided on its upper face with a series of radially extending grooves in which the sinkers 4 are mounted and guided. The sinkers are reciprocated by the usual sinker cam ring indicated at 5, which is provided 35 with a sinker operating cam rib 6. The sinkers are provided with the usual web holding hooks or fingers 7 which overlie the edge of the fabric when the sinkers are in the position indicated in Fig. 1, and hold down 40 the fabric as the needles rise through the loops, and which are withdrawn from holding position, as indicated in Fig. 2, when the needles are to draw new loops during the knitting operation. The outer ends of the 45 sinkers are prevented from rising in the sinker ring by the sinker cam ring which overlies them. The sinkers extend forward from the web retaining hooks and are guided and supported laterally by radial slots 8 50 formed in the upper end of the needle cylinder. The inner ends of the sinkers are held down by means of retaining fingers 9 which extend radially outward or rearwardly of the sinkers, and pass through guiding and retaining slots 10. The slots are formed in the 55 upper end of the cylinder immediately below the slots 8 from which they are separated by webs 11 which form a ring for holding down the inner ends of the sinkers. The 60 holding down fingers 9 pass into and out of the annular space 12 between the sinker ring and the upper end of the needle cylinder as the sinkers are reciprocated. With this construction, the inner ends of the slots or recesses 13 between the fingers 9 and the bodies

of the sinkers are open, so that the sinkers do not present shoulders opposing the shoulders formed by the outer side of the hold down ring 11 and no opposing surfaces are therefore presented upon the sinkers and hold down ring which move toward each other when the sinkers are advanced. The closed ends of the slots 13 in the sinkers are on the inner side of the hold down ring 11, and are thus within the needle cylinder 75 where they are covered by the fabric as it passes down within the needle cylinder, and where there will be comparatively little collection of lint. The space between the inner ends of the slots 13 and the inner side of 80 the hold down ring 11 are in free communication with the spaces between the sinkers, so that the lint may pass freely down between the sinkers. If any lint should collect in the space between the inner ends of 85 the slots 13 and the inner surface of the ring 11, this lint will not in any wise interfere with the forward movement of the sinkers into holding position, and may be readily and quickly removed by the operator without 90 requiring the removal of the sinkers. Any lint which may collect within the annular recess 12 will not interfere with the forward movement of the sinkers into holding position, and may be readily removed 95 through openings 14 formed in the sinker ring.

In order to enable the retaining and guiding slots for the inner ends of the sinkers to be conveniently and accurately formed, 10 these slots are formed in a throat ring 15 which is secured to the main part of the cylinder, and when in position, forms the upper end of the cylinder. The guiding slots 8 are formed in the upper edge of the throat ring, 10 while the retaining slots 10 are formed in the lower edge of the ring. The lower edge of the throat ring is recessed on its outer side to receive an annular rib 16 formed on the upper end of the needle cylinder, and the 11 throat ring is secured in position by a split ring 17 arranged to engage a recess 18 formed in the inner side of the throat ring. The split locking ring 17 is clamped in position by means of screws 19, as indicated in 11 Fig. 1.

By constructing the sinkers with rearwardly extending retaining or holding down fingers which project radially outward through retaining slots formed in the upper 12 end of the needle cylinder, the collection of lint which will interfere with the proper operation of the sinker is avoided, and a practically self cleaning sinker is provided which is efficiently held at its inner end against both 12 lateral and vertical movement.

While I prefer to employ the construction and arrangement of parts shown and described, it will be understood that this construction and arrangement is not essential to 130

the broader features of the invention, and may be changed and modified without departing from the invention.

Having explained the nature and object of 5 the invention, what I claim is:-

1. A circular knitting machine, having, in combination, a needle cylinder provided at its upper end with sinker retaining slots, and sinkers provided with hold down fingers having their free ends extending through the 10 slots rearwardly with relation to the working thrust of the sinkers, substantially as described.

2. A circular knitting machine, having, in combination, a needle cylinder provided at its upper end with sinker guiding and retaining slots, and sinkers arranged to extend through the guiding slots in the direction of the working thrust and provided with 20 hold down fingers extending through the retaining slots rearwardly with relation to the working thrust, substantially as described.

3. A circular knitting machine, having, in combination, a needle cylinder provided at 25 its upper end with a throat ring having radial slots on its upper and lower edges, means for securing the throat ring within the cylinder, and sinkers extending toward the center of the cylinder through the slots in 30 the upper edge of the ring and provided with

fingers extending radially outward from the center of the cylinder through the slots in the lower edge of the ring, substantially as described.

4. A circular knitting machine, having, in 35 combination, a needle cylinder, sinkers, and retaining and holding down devices at the inner ends of the sinkers having their opposing shoulders arranged to separate during the advance of the sinkers, substantially as 40 described.

5. A web holding sinker provided with a hold down finger having its free end extending rearward with relation to the working 45 thrust of the web holder, substantially as described.

6. A web holding sinker provided at its front end with a hold down finger 9 having its free end extending rearward with relation to the working thrust of the web holder, and 50 with a recess 13 between the finger and the body of the web holder, substantially as described.

In testimony whereof I affix my signature, in presence of two witnesses.

HARRY F. BERRY.
